TRANSMISSION LINE CONNECTOR

Herbert G. Koenig, Griggsville, Ill., assignor to Trio Manufacturing Co., Griggsville, Ill., a corporation of Illinois

Filed Sept. 29, 1958, Ser. No. 763,985

6 Claims. (Cl. 339—99)

This invention relates generally to antennas and more particularly, relates to an improved structure for a connector for coupling transmission lines to electrical signal translating apparatus, such as antennas, either of the transmitting or receiving type.

Although not specifically limited thereto, the transmission line connector embodying the invention is especially useful for connection of transmission lines of antennas designed to receive television signals over the present high and low frequency bands and in which the antennas are mounted outdoors exposed to the weather. Heretofore, the general practice of connecting transmission lines to the terminal lugs provided on such antennas has involved stripping off the insulation to expose the wire and then connection of the stripped wire to the terminal lugs. Various forms of wire holders often were employed as well as soldering of the terminal lugs to assure proper electrical contact and to maintain the connection over the life of the antenna installation. Such connections were exposed to the elements thereby giving rise to corrosion and possible short circuiting or opening of the connection. Frequently, the stripping operation accidentally caused weakening and breaking of the exposed wire strands such that after connection of the bared wire to the terminal lugs of the antenna, continued strain on the conductors caused them to break. Corrosion of the exposed wire also adversely affected the quality of reception of signals by the antenna whereby servicing and repair was the only solution.

Other problems arose from the use of heretofore known transmission line connectors in connection with installation of the antenna, especially in inconvenient or not readily accessible locations. The procedure of preparing the transmission line for connection to the antenna and actually connecting the line to the terminal lugs of the antenna involved multiple operations which could not be carried out most expeditiously where the antenna was being installed at such elevated sites as towers of tall buildings, roofs of multiple story structures, and the like or under such adverse conditions as strong winds, rain and snow. In addition, such adverse weather conditions subjected the connection of the transmission line to great stresses which were likely to break the connection where the bared wire had been weakened or strands thereof severed during the stripping of the insulation or connection of the bared wire to the terminal lugs.

Accordingly, it is the principal object of this invention to provide a transmission line connector for antennas which by reason of its advantageous construction substantially eliminates the disadvantages heretofore enumerated.

An important object of the invention is to provide a transmission line connector of the character described which eliminates the need for stripping of the transmission line in order to connect same to the terminal lugs of the antenna, which does not require soldering of the terminal lugs, which eliminates exposed wires at the point of connection of the transmission line and does not require any additional wire holders for maintaining the transmission line connection.

Another object of the invention is to provide a transmission line connector of the character described which includes a housing and means operable from exterior of

2

the housing for making the desired connection of said line with the antenna, said connection being established and maintained on the interior of the housing to the complete protection thereof.

A further object of the invention is to provide a connector of the character described in which there are provided connector means comprising tapered metallic components and a bearing block slideable on the interior of the housing, said metallic components and bearing block cooperable to clamp the line therebetween and effect penetration of the insulation of the transmission line for positive electrical contact completely protected on the interior of the shell and which utilizes the strength of the insulation of the transmission line to relieve strain on and maintain the desired electrical connection.

Still another object of the invention is to provide a transmission line connector of the character described which is comprised of a substantially reduced number of pre-formed parts capable of being assembled to form the connector whereby the cost of manufacture thereof is substantially reduced.

Other objects of the invention will be seen to reside in the provision of such an electrical transmission line connector for antennas which is distinguished by the simple and easy manner in which the connection of the line can be made and/or broken employing said connector, by the great strength of the connection afforded thereby, by the elimination of any need for tools or mechanical skill in order to effect the connection, the positive and permanent character of the connection afforded by the said connector and suitability of said connector for use with transmission lines of either flat, round or oval configuration.

With the foregoing and other objects in view which will appear as the description proceeds, the invention consists of certain novel features of construction, arrangement and a combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of this invention, there is illustrated in the accompanying drawing a preferred embodiment thereof, from an inspection of which, when considered in connection with the following description, this invention, its mode of construction, assembly and operation, and many of its advantages should be readily understood and appreciated.

Referring to the drawing in which the same characters of reference are employed to indicate corresponding or similar parts throughout the several figures of the drawing:

FIG. 1 is a perspective view of the transmission line connector embodying the invention, same being illustrated installed with pertinent portions of an antenna being shown.

FIG. 2 is a sectional view taken through the connector along line 2—2 of FIG. 3 and in the direction indicated.

FIG. 3 is a sectional view taken along the line 3—3 of FIG. 2 and in the direction indicated.

FIG. 4 is an exploded perspective view showing the slideable bearing member and a portion of one of the connector members which cooperate to penetrate the insulation of the transmission line in effecting electrical connection of said line.

FIG. 5 is a plan view of a fragment of a two-conductor transmission line showing the manner in which the insulation thereof is penetrated by the connector.

Referring to FIG. 1, the transmission line connector

embodying the invention is designated generally by the reference character 20. Also illustrated are pertinent portions of an antenna which may be any one of a great variety of reception or transmission antenna structures to which a transmission line is to be connected. Reference character 21 represents a portion of an antenna boom to which is mounted the insulation block 22. The block carries a pair of spaced apart terminal straps or lugs 23 secured on the upper surface thereof, each strap 23 having a downwardly offset terminal portion 24 extending outwardly of the longitudinal edge 25 of said block. A dipole element, a portion 26 of which is illustrated, is secured in electrical connection with each of said terminal straps by means of the bolt 27 extended through suitable perforations in the block and adjacent terminal strap and the wing nut 28. The transmission line is designated 29 and same has a conductor thereof electrically connected to terminal portion 24 of each terminal strap by means of the connector 20. The invention illustrates and was especially intended for use with the well-known flat 300-ohm transmission line used with television and radio receiving antennas. The invention is not limited thereto, however.

The connector 20 is comprised generally of a mounting base or platform 30, a shell 31 secured on said base or platform, a pair of connector members 32 cooperably associated with a bearing or clamping block 33 slidable on the interior of the shell for clamping the line and penetrating the insulation of the transmission line so that each conductor of the line is electrically connected to a terminal strap 23 and hence, a dipole or other antenna element 26, and actuator means for selectively sliding said bearing block 33 relative said connector members. It should be understood that the order of enumeration of the various component parts of the unitary connector structure 20 does not reflect their relative importance in said structure. Each of said component parts will now be described in detail.

The base or platform 30 preferably comprises a molded member of a suitable insulative material, such as a thermo-setting or thermo-plastic resin, ceramic and the like. Said base 30 is generally rectangular in configuration and the upper surface 35 thereof may be formed with elongate upstanding ridges 36 parallel along the length of the member to strengthen said base. A transverse medial upstanding ridge 37 interconnects said ridges 36 and on opposite sides of ridge 37 is provided a pair of passageways 38 extending transversely through the base, each passageway 38 continuing into a hollow, annular boss or ring 39 upstanding on said surface 35. As seen in FIG. 2, the ridges 37 taper upwardly toward the transverse center line of the base and level off on opposite sides of said center line to provide a somewhat thickened flat medial portion designated 40. The bottom or opposite surface 41 of the base may be seen to be generally flat.

Shell 31 preferably also is formed as an integral molded member and may be of the same insulative material as the base 30. Said shell includes a pair of parallel side walls 42 connected between and perpendicular to the parallel lateral walls 43 and an end wall 44, the thickness of which is substantially greater than that of the walls 42 or 43. Since the connector is installed in a vertical position depending relative boom 21 as seen in FIG. 1, the end wall 44 may be considered the bottom end wall of the shell. The opposite or upper end 45 is open for a special reason subsequently to be explained. Each of the walls 43 may be seen to be of identical, generally isosceles trapezoidal configuration with the wider dimension thereof adjacent said upper or open end 45. Walls 43 each have oppositely extending planar segments 46 which protrude outwardly of the plane of a wall 42, and walls 42 each have a right angle flange 47 extending outwardly therefrom and conjoined with the segments 46 at the upper end of the housing.

Each wall 43 has a passageway therein leading to the interior of the shell, said passageway provided by a recess or slot 48 opening to the upper horizontal edge of each wall. On opposite sides of said passageway, each 5 wall 43 has an outwardly tapered bead formation 50 which is flush with the upper end face of said wall as indicated at 51 in FIG. 3, said slots 48 opening each to a said end face 51. Referring to FIG. 3, it will be seen that end face 51 of each wall 43 protrudes slightly beyond the upper free edge of flange 47 to which said wall 43 is conjoined thereby giving rise to the clearance spaces 52 each extending the width of a wall 42.

Each flange 47 has a passageway 53 transversely therethrough which connects with an annular ring 54 upstanding from the bottom surface of the flange in the installed position of the connector. The passageways 53 are spaced apart laterally the same distance as the passageways 38 in base 30 whereby said passageways can be aligned for reception of metal fasteners therethrough, such as rivets 55 supported at their headed ends respectively on the annular rings 39 and 54 for securing the shell 31 to the base 30. In secured position, the shell 31 depends from the bottom planar surface 41 of the base with open end 45 of the shell facing said surface 41.

25 The connector members 32 each comprise a flat strip of conductor material, such as copper, silver and the like, each strip being substantially L-shaped in configuration. Shorter leg 58 of the strip is connected to the longer leg 56 along a line of bend, which is diagonal to 30 the length of leg 56. Each leg 58 is notched or serrated along the free edge thereof to provide a series of tines or prongs 57, the ends of which are sharply pointed. As seen in elevational view, the tines 57 are triangular in configuration to provide considerable strength in the 35 plane thereof and have their pointed ends arranged parallel to said diagonal line of bend.

The connector members are installed with the shorter legs 58 facing one toward the other and spaced apart and parallel one relative the other and with tines 57 extending into the shell through the upper or open end 45 thereof generally perpendicular to the end wall 44. Thus, tines 57 actually face downwardly in the installed 40 condition of the connector. The longer legs 56 extend in opposite direction and each has a surface thereof in contact with the surface 41 of the base. Each leg 56 is 45 passed through a said space 52 outwardly of the shell and has an opening therein through which the rivet 55 extends. Adjacent the free end thereof, each leg 56 has a circular opening 58' therethrough which is aligned with a similar transverse opening 59 in the base 30, said 50 openings 59 being located adjacent the extremities of the base.

It will thus be seen that connectors 32 each have a portion 60 thereof extending outside of shell 31 and exposed on the bottom surface 41 of the base.

55 Bearing or clamping block 33 preferably is a pre-formed molded member which can be made of the same material as the base 30 and shell 31. As seen in FIGS. 3 and 4, block 33 comprises a rectangular solid having a planar bottom surface 61, a pair of parallel lateral faces 62 generally normal to surface 61 and end faces 63. The rectilinear configuration of surface 61 is complementary to the cross-sectional configuration of the interior of the shell 31 along a horizontal plane therethrough and related dimension-wise to permit the block 60 33 to be inserted through the open end 45, surface 61 first, prior to attachment of the shell 31 to the base 30. Thus installed in the shell, surface 61 faces the inner surface of wall 44, surfaces 62 each face the inner surface of a wall 42 and end faces 63 each face the inner 65 surface of a wall 43, and the block is slidable in the shell substantially guided by said walls 42 and 43. The thickness of said block is substantially less than the distance between the pointed ends of the tines 57 and the inner surface of end wall 44 so as to permit such sliding 70 movement of the block.

The surface 64 of block 33 opposite bottom surface 61 thereof has an elongate guide groove or depression 65 of a step-down formation, the opposite ends of the groove 65 opening to the end faces 63. Groove 65 has a pair of vertically arranged lateral surfaces 66 convergently tapered toward the bottom surface 67 which each connect with a shoulder formation 68 spaced above and on opposite sides of bottom surface 67. There are a pair of parallel channels 69 and 70 formed on a bias or diagonally in said block which open to the upper surface 64 and being of sufficient depth to extend through a shoulder 68 to the bottom surface 67 of the groove. Also, said channels each open to a surface 62 adjacent opposite end faces 63. The linear distance between the longitudinal centers of said channels 69 and 70 is approximately equal to the linear distance between oppositely facing tines of legs 58 of the connector members, so that each of said channels opens to said upper surface 64 of the block aligned with a short leg 58 of the connector member. In the installed position of the block, the groove 65 will be seen to be aligned lengthwise with the slots 48 in the walls 43.

The actuator means 34 comprises a plunger member in the form of a threaded shank 71 threadedly engaged through opening 72 in the bottom wall 44 with a nut 73 seated in a suitable depression in the inner surface of said wall. The shank has a knurled head 74 secured to one end thereof exterior to the shell, the inner end 75 of the shank arranged opposite a metal disc 76 seated centrally in the surface 61 of the block 33. The axis of the shank 71 is generally perpendicular to the plane of surface 61 of the block and end wall 44 of the shell. By advancing the shank 71 in said wall 44, end 75 will bear against disc 76 and translate the block 33 linearly toward the open end 45 of the shell and the pointed tines 57.

We consider the operation of connector 20. Same is installed as seen in FIG. 1 supported on the protruding terminal portions 24 and secured in place by suitable fasteners such as round head bolt 77, each engaged through an aligned pair of passageways 58 and 59 and the adjacent terminal portion 24. Each terminal portion 24 has the exposed portion 60 of a connector member 32 physically engaged therewith and hence, electrically connected thereto. The shell 31 depends between said terminal portions 24. The shank 71 is retracted so that the block 33, freely slidable in the shell will follow in engagement with the inner end of the shank. As block 33 moves toward the bottom end wall 44, the opposite open ends of the groove 65 are exposed in the slots 48 and a passageway through the shell is provided between the pointed ends of tines 57 and the upper surface 64 of the block.

The transmission line 29 is then inserted through a slot 48 into the shell between the block 33 and the tines 57 aligned with the groove 65 and out through the slot 48 in the opposite wall 43 any desired distance. The knurled head 74 is rotated to take up on the shank 71 and slide block 33 toward the tines 57. The line 29 will be supported in groove 65 on the shoulders 68 and continued sliding movement of the block 33 will cause the tines 57 of each leg 55 to enter a channel 69 or 70 and bear against the transmission line. Continued pressure exerted by the bearing block 33 will cause the pointed ends of the tines to pierce the insulation of the line 29 and eventually engage against the bottom surface 67 of the groove 66 with said line clamped between block 33 and said connector members 32. Referring to FIG. 5, the pattern of the penetration effected by tines 57 is illustrated as a pair of spaced apart parallel rows 80 of perforations extending diagonally at least halfway across the transmission line 29. This pattern will be seen to provide a row 80 of perforations which cuts across each of the conductors 81 of said line thereby electrically connecting each of the connector members

32 with a said conductor. The conductors usually are formed of wire strands which permit the tines 57 easily and readily to penetrate therethrough.

It will thus be seen that the connector 20 eliminates the necessity for stripping of line 29 to expose conductors 81 in order to connect said line to the antenna. The connection is made entirely within the shell 31 thereby affording protection of said connection from rain, snow and other elements of the weather likely to corrode the conductors 81 or the connector components. Since the tines 57 engage through the insulation of line 29, the strength of the insulation material is added to the connection. Strain on the connection is relieved by reason of the length of the line 29 which is supported on the length of the shoulders 68. The connection is therefore substantially stronger and more permanent. Penetration of the teeth or tines 57 assures positive electrical connection of members 32 with the conductors 81, such connection being accomplished merely by rotating the plunger means. To sever the connection, shank 71 need only be retracted thereby withdrawing the block 33 and the line 29 pulled free of the tines 57. The connector 20 can accommodate transmission lines of either flat, oval, circular or other configuration with equal facility.

Variations in the structure described and illustrated are possible without departing from the principles of the invention. For instance, the inner end 75 of the plunger means may be physically connected to the block 33. The plunger 71 may be provided merely to slide in the opening 72 instead of being rotatably mounted in the wall 44. Other means for installing the connector may occur to the skilled artisan as well as different ways and materials for making the component parts of the connector. In its broad aspect, the invention provides for a connector which includes means for mounting same in operational position on the antenna, a housing depending from said mounting means, electrical connector means on the interior of the housing for connecting each conductor of the transmission line to an element of the antenna and bearing means cooperable with said connector means from the exterior of the shell or housing for effecting said connection, said electrical connection being characterized by the elimination of any stripping of the insulation of the transmission line and by the protected character of the connection on the interior of the shell or housing.

It is believed the invention has been described in sufficient detail to enable the skilled artisan to understand and practice the same as required by the patent statutes. The invention has been pointed out in claims hereto appended, it being intended the language of these claims be construed in their broadest aspect commensurate with the contribution to the arts and sciences made by same.

I claim:

1. A connector device for electrically connecting conductors of a transmission line to terminals of an antenna, said device comprising a base for installing the device on the antenna, a housing depending from said base having a transverse passageway therethrough, connector members on the interior of the housing and extending outwardly through opposite walls of the housing for electrical connection with said terminals respectively, a slideable bearing member on the interior of the housing and movable toward and away from said connector members, an actuator member operable from exterior of the housing for sliding the bearing member toward the connector members, said device operable to receive the transmission line in said passageway between the connector members and the bearing member, said connector members having means for piercing the insulation of the transmission line to electrically connect each of said conductors thereof to a terminal of the antenna, said actuator member operable to clamp the line between said bearing member and connector members to cause said insulation to be pierced entirely within said housing, said connector members each comprising a substantially L-shaped

strip having the shorter leg thereof on the interior of the housing, each shorter leg having pointed formations facing toward the bearing member providing said piercing means, said bearing member comprising a block having a guide groove in a surface thereof opening toward the shorter legs and adapted to be aligned with said passageway to receive the transmission line therein, and channel formations opening to said surface each aligned with a said shorter leg, said channel formations and pointed formations arranged angularly disposed relative to the length of said transmission line seated in the groove.

2. A connector device for electrically connecting conductors of a transmission line to terminals of an electrical signal translating apparatus comprising, a base for installing the device on the apparatus, an insulative, box-like housing supported on the base, said housing having a transverse passageway therethrough, connector members on the interior of the housing having terminal segments exterior of the housing for electrical connection to the terminals of the apparatus, a bearing member slideable on the interior of the housing toward and away from said connector members, an actuator member operable from exterior of the housing for selectively sliding said bearing member, said connector members each having insulation piercing means for electrically connecting said conductors to the terminals of the apparatus comprising tapered means facing toward the bearing member, said bearing member having a guide groove in a surface thereof opening toward said tapered means and adapted to be aligned with said passageway to receive the transmission line therein and channels opening to said surface, each channel being aligned with one of said tapered means, said channels and tapered means being arranged angularly disposed relative to the length of the groove, said bearing member adapted to have the transmission line seated in said groove and thereafter slide toward said tapered means whereby to engage said tapered means in said channels in electrical connection with the conductors.

3. A connector as described in claim 2 in which the inner surfaces of said housing are arranged to guide the movement of said bearing member in the interior of the housing.

4. A connector device for electrically connecting conductors of a transmission line to terminals of an antenna comprising, a base for installing the device on the antenna, an insulative housing secured to said base having a transverse passageway therethrough, connected means on the interior of the housing having connector portions exterior to the housing for electrical connection to said terminals respectively, a slideable insulative bearing block on the interior of the housing and movable toward and away from said connector means, a plunger operable from exterior of the housing for sliding the block member toward the connector means, said block member having a groove for seating the transmission line when aligned with said passageway, said connector means including insulation piercing means to electrically connect each of said conductors to an antenna terminal, said piercing means being arranged in substantially parallel planes diagonal to the groove and said block having channels arranged in complementary alignment with said piercing means, said plunger operable to slide the block to engage said piercing means in said channels to electrically connect the conductors of the transmission line seated in the groove to said terminals entirely within the housing.

5. A connector structure of the character described for establishing electrical connection between the respective conductors of a relatively flat, flexible, two conductor transmission line cable having said two conductors embedded in insulating material parallel one to the other, and two other conductors which comprise a housing having a chamber opening to the exterior thereof, a pair

of toothed members of conducting material mounted in the chamber and each having a plurality of teeth arranged to pierce the insulating material along a diagonal line intersecting the longitudinal axis of the cable commencing from an opposite edge of the cable and entirely within the housing chamber, each toothed member metallically connected with said other conductors, terminal means on the exterior of the housing electrically connected with said toothed members for electrical connection with said other conductors, a pressure member in said chamber aligned with said toothed members and having a guide groove adapted to be aligned with said chamber opening for seating the cable therein, means connected with said pressure member and operable from exterior of the housing to force the pressure member and toothed members together upon said cable with the toothed members intersecting said guide groove, said toothed members being arranged in parallel planes diagonal to the length of the groove, said guide groove formed of a bottom wall and a pair of walls upstanding along opposite edges of the bottom wall, said upstanding walls having ledge formations equally spaced from the bottom wall and arranged to support the cable thereon in said guide groove, said upstanding walls each having a diagonal channel therein opening to the upper end of the upstanding wall and intersecting the ledge formation thereof, each channel being aligned with a toothed member, said toothed members each adapted to be received in a said channel to pierce said insulation with the cable supported on said ledge formations.

6. A transmission line connector for establishing an electrical connection between a two-conductor electrical transmission line and respective other conductors comprising, a housing having an opening through which said transmission line can be extended, a pressure member having a guide groove having a bottom wall and opposite side walls of step-formation to provide support ledges for the transmission line spaced above the bottom wall, said pressure member being movable in said housing for aligning said guide groove with said opening to permit said transmission line to be introduced through said opening into the guide groove to be supported on said ledges, said side walls having a pair of channels each extending along a respective line having only one intersection with the longitudinal axis of the transmission line and the guide groove, a pair of serrated members carried by the housing with the serrations of each member opposing said pressure member and aligned with a respective one of said channels, and means for applying pressure from said pressure member to said transmission line when so supported in the guide groove and against serrations of said respective serrated members to pierce the transmission line insulation and establish an electrical connection between a serrated member and one conductor of the transmission line, said channels arranged to permit sufficient engagement of said serrated members therein to enable said insulation to be pierced with said transmission line supported in a strain relieved position on said support ledges.
